UNITED STATES PATENT OFFICE.

THOMAS P. ARCHER AND FRANK M. EDGAR, OF DETROIT, MICHIGAN, ASSIGNEES TO
TERNSTEDT MANUFACTURING COMPANY, OF DETROIT, MICHIGAN, A CORPORATION
OF MICHIGAN.

WINDSHIELD REGULATOR.

Application filed July 29, 1925. Serial No. 46,828.

This invention relates to windshield regulators in the so-called Fisher V-V windshield, which is a single panel, up and down sliding windshield controlled by a window regulator, certain difficulties have been met with in the breaking of the window regulators.

This condition has been due to the fact that a windshield panel is a relatively heavy panel and it requires a regulator which has relatively great mechanical advantage for raising and lowering. The result has been that where the operator continued to exert effort on the operating handle after the shield is stopped, either at the top or bottom, it very often stripped a gear. For instance the ratio of mechanical advantage is something like 7 to 1. 100# effort on the handle is translated into 700# on the shield and on the last operating gear. It will be evident that under these conditions it has been very easy to strip a gear or break some of the other parts. It is the object of the present invention to overcome this difficulty.

To that end a suitable stop mechanism is afforded which resists the operating effort before this has been multiplied by the mechanical advantage referred to.

In the drawings:

Fig. 1 is a cross section, fragmentary in character, through the top of a closed body, looking at the inside of the header and showing in dotted lines the window regulator installation.

Fig. 2 is a section on the line 2—2 of Fig. 1.

Fig. 3 is an elevation of the improved window regulator.

Fig. 4 is a fragmentary elevation of the same, showing how the stops engage.

a designates the roof of a closed car, *b* the inside header board, and *c* the windshield. In Fig. 1 the several operating parts of the windshield regulator are shown in dotted lines. In Fig. 3 these parts are shown in elevation. Briefly, these are the supporting plates *d* and *e* connected by the spacing strap *f*. A driving pinion *g* is operated by a han-

dle *h* through the interposition of a clutch, the details of which are not shown here, but which are indicated in a general way at *i* in Fig. 2. This clutch in the usual way serves to lock the windshield at any given position. This pinion *g* meshes with the intermediate gear *i*, to which is fastened another pinion *j*, which meshes with the final driven gear *k*. To this is attached a crank arm *m* having a crank pin *n* arranged to engage a loop secured to the top of the shield to raise and lower the shield.

Similarly a gear *o*, a crank arm *p* and a crank pin *q* on the opposite end of the regulator lifts the opposite end of the windshield, the effort being transmitted from the driven gear *k* to the driven gear *o* by means of a sliding rack *r* and a pinion *s*.

This much of the construction is old and is claimed in previous applications. However, the multiplication of effort by leverage is considerable. The purpose of the present invention is to stop this turning effort on the handle at the appointed time before the same has been multiplied by the gear ratios. This is accomplished in a very simple and efficient manner by providing a disc *t* attached to the driving pinion *g* and which is provided with a stop projection *u*. On the intermediate gear is stamped out a stop *w*.

Now this disc and the position of the stop on the intermediate gear are of such size and in such position that they are calculated to collide or meet only once, say in five or six rotations, whatever is necessary to get the correct travel for the windshield. This, of course, may be easily varied by changing the diameter of the disc and the radial distance of the stop from the center of the disc and the radial distance of the stop from the center of the intermediate gear. The point is that at definite and determined points in the turning of the gears, the two stops meet and stop the train of gears. This stop is effective on the driving pinion without any multiplication of the effort.

What we claim is:

In a window regulator, the combination of

means for raising and lowering the window, an operating handle free to rotate, means for transmitting the effort, said means including a plurality of gears, and a pair of shoulders connected with said gears and arranged to collide after a definite number of rotations of one gear and a different number of rota-

tions of the other gear, thereby stopping operating effort before the same has reached its maximum condition.

In testimony whereof we have affixed our signatures.

THOMAS P. ARCHER.
FRANK M. EDGAR.
